UNITED STATES PATENT OFFICE.

LOUIS JUDELSON, OF NEW YORK, N. Y.

CLOTHES WRINGER.

Application filed November 7, 1924. Serial No. 748,318.

This invention relates to clothes wringers, and more particularly to an improved drive and safety device control for wringers and the like class of apparatus.

5 An object of the invention is to provide a device of the character described which may be readily installed for household use or use in connection with washing machines and which includes practical operating control 10 means that serve to facilitate safeguarding the operator and protecting the driven machine.

Another object of the invention is to provide a device of the character described which 15 is simple in construction, inexpensive to manufacture, and efficient in operation to a high degree.

Other objects of this invention will in part be obvious and in part hereinafter pointed 20 out.

Certain features herein shown and described are shown, described, and claimed in my Patent 1,538,993 granted May 26, 1925, and therefore are not claimed herein.

25 The invention accordingly consists in the features of construction, combinations of elements and arrangement of parts which will be exemplified in the construction hereinafter described and of which the scope of application 30 will be indicated in the following claims.

In the accompanying drawing, in which is shown one of the various possible illustrative embodiments of this invention,

Fig. 1 is a front elevational view, with parts 35 broken away, showing the wringer together with a motor for operating the same mounted as a unitary structure and installed on a wash tub for household use;

Fig. 2 is a cross-sectional view taken on line 40 2—2 in Fig. 1;

Fig. 3 is a plan view of an installation embodying the invention;

Fig. 4 is a view similar to Fig. 1 but showing an interconnecting means for shutting off the power to the roll drive simultaneously 45 with the release of the roll tension control; and

Fig. 5 is a cross-sectional view taken on line 50 5—5 in Fig. 4 of the rolls and guard member.

Fig. 6 is a plan view of the top of the wringer frame.

Referring in detail to the drawing, 10 is a wringer machine frame consisting of upright standards 11, 11' secured to the base 12 and a cross member 13 normally fastened to the

upper ends of said standards 11, 11' as shown in Fig. 1. The standards 11, 11' carry the gear casings 14, 14' in which are housed the pairs of gears 15, 15' and 16, 16'. The lower gears 15, 16 are supported on a horizontal 60 shaft 17 which in turn is journaled in bearings 18, 18' in the standard 11, 11'. The shaft 17 extends at one end 17^a thereof into the transmission box 19 supported on the base 12 by any suitable means, such as the bolts 65 19^a. Supported above shaft 17 is the upper shaft 20 journaled in a pair of vertically movable bearing blocks 21, 21' mounted in the standards 11, 11'. The shafts 17 and 20 carry the usual wringer rolls 22, 23. Mounted 70 on the front and rear sides of the gear casings 14 and 14' are brackets 24 and 24' which are adapted to removably support a guard member 25 therebetween. Said member 25 is provided with a slotted portion 25^a to permit 75 feeding therethrough the clothes to be wrung, the flanged sides 25^b of member 25 serving to prevent the accidental insertion of the operator's fingers between the rolls 22 and 23. The bearing blocks 21, 21' are recessed 80 as at 26, 26' to provide seats for the lower ends of the tension springs 27, 27'. The upper ends 28, 28' of these springs are disposed in similar inverted recessed portions 29, 29' formed in the presser blocks 30, 30', 85 at the ends of the tension bar or cross member 31. The presser blocks are preferably formed integral with said tension bar. For tensioning the rolls 22, 23, pressure is applied 90 to the tension bar 31 by means of the hand wheel 32 having a threaded shank 32' extending through a central opening 33 of the cross member 13.

Power means is provided for rotating the rolls 22, 23 and for reversing the direction of rotation thereof when desired. To this end a reversing power drive is provided for one of the shafts, such as the lower shaft 17, comprising a pair of beveled gears 34, 34' mounted in opposed relation to each other 100 and at right angles to a gear 35 and in operative relation thereto. The latter is driven by the power shaft 39 which may be operated by any suitable power means, as for example motor 40, and a suitable reduction gearing which may also be included in said power drive. In the form shown in the drawings, the motor shaft 39 drives a worm 41, which in turn drives a worm gear 43 mounted on the same shaft with the gear 35. A clutch 110

36 is provided for throwing either one of the gears 34, 34' into mesh with the driving gear 35. This clutch is operated by a link member 37 pivoted to a horizontal arm 38 extending 5 across the wringer beneath the rollers. This arm 38 is provided with an operating handle 38^a and notches 38^b, 38^c, and 38^d whereby the arm may be held in adjusted position, by selectively engaging said notches with a de- 10 tent member 50. (See Fig. 1.)

As will be clear from the drawing, when link member 37 is in position A, bevel gear 34' is in mesh and shaft 17 will be driven in one direction; and when the link is in the 15 position shown at C, the bevel gear 34 will be in mesh and the shaft driven in the opposite direction. When the link is in the neutral position B, the shaft is at rest.

The means for separating the upper 20 wringer roll 23 from the lower roll 22 will now be described. Straddling each end 13^a, 13^b of the cross member 13 are the keepers 42, 42' preferably inverted U-shaped. The 25 keepers 42, 42' extend downwardly over the cross member 13 and are pivotally secured as at 43, 43' to the standards 11, 11'. A hand lever 44 is provided which may be pivoted by means of a pin 44^c to the cross member 13. This hand lever carries a pair of link arms 30 45, 45' for connecting the keepers 42, 42' respectively thereto. The arm 45 is pivotally connected to the lower end of the lever 44, and is pivoted at the other end to the keeper 42. The arm 45' is pivotally secured to the 35 lever 44 above the pin 44^c and at the other end to the keeper 42'.

The operation of the safety device for the separation of the rolls will now be clear. When the lever 44 is in inclined closed position, as shown in full lines in Fig. 1, the keepers 42, 42' straddle the cross member 13, thus 40 holding the tension bar 31 down with the presser blocks 30, 30' thereof compressing the springs 27, 27'. The wringer rolls are then in operative position and under proper 45 tension as previously adjusted by the hand wheel. If the operator should get a hand caught between the rolls, he quickly strikes the hand lever 44 throwing it into open position shown in dotted lines in Fig. 1. The link arms 45, 45' connected to the hand lever will then push outward on the keepers 42, 42' causing them to rotate out of holding 50 position, thus releasing the presser bar 31 and cross member 13. The bearing blocks 21, 21' will then be released to permit upward movement of the shaft 20 with the roller 23 thus quickly freeing the hand. The rolls may then be re-set for operation by 55 turning the hand wheel 32 to release the tension, swinging the hand lever 44 down to simultaneously restore both the keepers to their effective position, and then readjusting the tension applied to the rolls by 60

turning said wheel 32 as will be readily understood.

The wringer may be mounted in the form of a unitary device adapted for household use or in combination with washing machines. In the former case base member 12 70 may be pivotally secured as at 49 adjacent one end of the rear wall of a wash tub 51, and mounted adjacent the pivoting point 49 is the motor 40 and transmission box 19 as already described. For clamping the 75 wringer and motor accessories in position, the free end 48 of the support 12 is provided with suitable clamping means, such as a spring catch comprising a shank 52 which extends through the support 48 and carries 80 a spring 53 which normally urges a clamp member 54 in straddling holding position over the wall 55 of the tub. In this way, a complete unitary motor operated wringer is provided which may be easily swung into and 85 out of operative position and secured in place.

By the arrangement of the roller releasing lever 44 and drive control arm 38^a on the same end of the wringer and within 90 convenient reach of the operator, as shown in Fig. 1, practical and efficient means are provided to facilitate the safeguarding of the operator and the machinery, since the rollers 22, 23 may be easily and quickly stopped, 95 reversed, and separated, selectively or committently as desired.

In Fig. 4 is shown a modified embodiment of the invention which includes means for interconnecting the wringer roller tension 10 releasing control with the roller drive control. Said means comprises a pivoted releasing detent member 60, in place of the stationary member 50, shown in Fig. 1. Said member 60 is connected in any suitable manner to the keeper 42', as by means of the link 61, the lower end of said link being provided with an elongated slot 70 wherein projects a pin 71 mounted on said detent member to form a lost motion connection 11 therebetween, as shown in Fig. 4. In order that the clutch may be returned to the off or non-driving position when the detent member 60 releases the arm 38, a pair of opposing springs 62 is provided, each spring 11 having one end anchored on the transmission box 19 on opposite sides of link member 37, the other ends being secured to said member 37.

The operation of the above described interconnected control means will now be apparent. With the lever 44 in effective tension position, the detent member 60 is in raised position and the roll drive control may be operated in the usual manner by 12 manipulation of the arm 38. On raising the lever 44 to release the tension on the wringer rolls, the detent member 60 is de-

pressed, thus releasing the arm 38 and permitting the spring 62 to throw the clutch to off position. Thus the lever 44 controls the releasing of the rolls and simultaneously is effective to cut off the driving power.

It will thus be seen that there is provided a device in which the several objects of this invention are achieved and which is well adapted to meet the conditions of practical use.

10 As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

20 1. In a device of the character described, in combination, a pivoted support, a clothes wringer mounted on said support, a power means on said support between said pivot and said wringer, a transmission mechanism connecting said power means and said wringer, said mechanism having control means for reversing said wringer, and for operatively disconnecting said wringer from said power means, said power means, transmission mechanism, and clothes wringer being mounted on said support in alignment for swinging movement, and control actuating means for said mechanism slidable in the plane of said power means, transmission mechanism and clothes wringer and extending beyond the end of said wringer.

2. In a device of the character described, in combination, a clothes wringer mounting on a pivoted support, power means for the wringer mounted on said support in alignment with said wringer and between said pivot and said wringer, and control means for said power means extending beyond said power means and wringer and slidable in the plane of alignment.

3. In a device of the character described, in combination, a support pivoted at one end thereof, a clothes wringer having a plurality of rolls mounted on said support for swinging movement therewith, means for maintaining said rolls in yielding contact, means for releasing said maintaining means, power means for said wringer mounted on said support between said wringer and pivot and in alignment therewith, a control device for said power means, said releasing means and control

device extending at the side of said wringer opposite to that at which the power means is mounted, and operable in the plane of alignment.

4. In a device of the character described, in combination, a pivoted support, a clothes wringer maintained on said support, a power device for said wringer mounted on said support in alignment with said wringer and between said wringer and pivot, and control means for said power device extending on the side of said wringer opposite to that at which the power means is mounted.

5. In a device of the character described, in combination, a clothes wringer having a plurality of rolls, means for maintaining said rolls in yielding contact, means for releasing said maintaining means, power means for said wringer, a control device for said power means, means co-acting with said control means for normally maintaining said power means inoperative, and means for retaining said control means in position for making said power means operative, said retaining means being operatively connected with said releasing means for automatically releasing said retaining means upon actuating said releasing means.

6. In combination, a single elongated support, a wringer and motor therefor mounted on said support, said support being pivotally mounted at one end and carrying clamping means at the other end, said wringer and motor being mounted between the pivot point and said clamping means.

7. In a device of the character described, in combination, a clothes wringer having a plurality of rolls, means for maintaining said rolls in yielding contact, means for releasing said maintaining means, power means for said wringer, a control device for said power means, tension means operatively connected with said control means tending to move said control means to position for making said power means inoperative, means for retaining said control means in position for making said power means operative, and means operatively connecting said retaining means with said releasing means for automatically releasing said retaining means and permitting said tension means to move said control means to inoperative position upon actuating said releasing means.

In testimony whereof I affix my signature.

LOUIS JUDELSON.
